UNITED STATES PATENT OFFICE.

ROBERT LEE LANIER, SR., OF MONTICELLO, KENTUCKY.

HARMONICA.

No. 925,778.

Specification of Letters Patent.

Patented June 22, 1909.

Application filed March 14, 1908. Serial No. 421,154.

To all whom it may concern:

Be it known that I, ROBERT LEE LANIER, Sr., a citizen of the United States, residing at Monticello, in the county of Wayne, State 5 of Kentucky, have invented certain new and useful Improvements in Harmonicas; and I do hereby declare the following to be a full, clear, and exact description of the invention, such as will enable others skilled in 10 the art to which it appertains to make and use the same.

This invention relates to musical instruments and more especially to an improved form of harmonica.

15 One object of the invention is to arrange an harmonica so that the number of air ducts may be increased without rendering the instrument clumsy to handle.

The invention consists in certain novel 20 details of construction and combinations of parts hereinafter more fully described, illustrated in the accompanying drawings, and specifically pointed out in the claims.

In the accompanying drawings, Figure 1 25 is a side elevation of the harmonica embodying my invention, Fig. 2 is a top plan view thereof, Fig. 3 is a view similar to Fig. 2 but with the top face plate removed, Fig. 4 is a bottom plan view of the harmonica, 30 and, Fig. 5 is a vertical sectional view therethrough.

As shown in the drawings, the harmonica embodying my invention comprises, in part, 35 an annular reed carrying member consisting of an annular element 10 formed in each of its faces with one or more series of channels 11, and reed plates 12 which are secured to the faces of the element 10 and are formed each with one or more series of openings 13 40 which register with the channels 11 of the element 10. The channels 11 open through the outer periphery of the said element and form, in connection with the openings 13, the air ducts of the instrument, there being 45 reeds 14 secured upon the reed plates 12 and normally closing the openings 13 as is usual in harmonicas, the reeds being arranged upon corresponding faces of the reed plates so that certain of the reeds may be sounded 50 by forcing a current of air into the corresponding channels 11 and the other reeds upon the other reed plate by inducing, by suction, a current of air through the other channels 11.

55 Secured removably, preferably by means of screws 15, to the under side of the under

reed plate 12 is a bottom face plate 16 and secured in a similar manner to the upper side of the upper reed plate 12 is a top face plate 17. This last mentioned face 60 plate 17 is concavo convex in form whereas the plate 16 is substantially flat and the plate 17 is formed centrally with an air outlet opening 18, it being understood that an air chamber is formed between these two plates 65 16 and 17 and that the air forced into the chamber or drawn through the same is taken in or let out through the opening 18, and it will further be understood that by governing the size of this opening the tone of a 70 note being sounded may be modulated if so desired, the result being accomplished by placing one finger over the opening and it will further be apparent that by rapidly raising and lowering the finger to rapidly 75 cover and uncover the opening, a tremolo may be produced.

Two or more scales or series of ducts may be formed throughout the circumference of the harmonica, each series representing a 80 scale in a different key, thus for example the series extending from *a* to *a* in Fig. 3 may represent a scale in the key of C, those extending from *b* to *b* in this figure a scale in the key of G and those from *c* to *c* a 85 scale in the key of F, it being understood of course that these keys are arbitrarily named and that any other combination of keys may be provided, also that any number of different keys may be provided within 90 the limit of the circumference of the instrument.

As is usually the case, my instrument is intended to be placed upon the market with the scales of the several keys increasing in 95 pitch from left to right but as it is desired by some musicians to have the increase in pitch extent from right to left, both face plates 16 and 17 are, as heretofore stated, removably secured in place and as a consequence, they may be interchanged so as to invert the annular member of the instrument, the face plate 17 being at all times the upper plate.

What is claimed, is:—

1. A harmonica comprising an annular reed supporting member having air ducts extending radially from the periphery of the member to the reeds, and a wind-chest inclosing the reeds.

2. A harmonica comprising an annular member having air ducts extending radially

105

110

from its periphery, reeds mounted on said member over the inner ends of the air ducts, and arranged in groups pitched in different keys, and a wind-chest inclosing the reeds.

5 3. A harmonica comprising an annular member having air-ducts extending radially from its periphery, reeds mounted on said member over the inner ends of the air ducts and arranged in pairs, the members of each

pair being reversely arranged, and a wind-chest inclosing the reeds.

In testimony whereof, I affix my signature, in presence of two witnesses.

ROBERT LEE LANIER, Sr.
